UNITED STATES PATENT OFFICE

GEORGE S. LEWIS, OF EVANSTON, ILLINOIS, ASSIGNOR TO METAL SPECIALTIES
MANUFACTURING COMPANY, OF CHICAGO, ILLINOIS, A CORPORATION OF ILLINOIS

DESIGN FOR A BICYCLE FRAME

Application filed May 16, 1932. Serial No. 43,811. Term of patent 7 years.

To all whom it may concern:

Be it known that I, GEORGE S. LEWIS, a citizen of the United States, residing at Evanston, in the county of Cook, State of Illinois, have invented a new, original, and ornamental Design for a Bicycle Frame, of which the following is a specification, reference being had to the accompanying drawing, forming a part thereof, in which—

Figure 1 is a side elevation of a bicycle frame showing my new design; and

Figure 2 is a perspective view of the same, but on a somewhat reduced scale.

I claim:

The ornamental design for a bicycle frame as shown.

GEORGE S. LEWIS.
